UNITED STATES PATENT OFFICE.

SAMUEL G. MUSSER, OF LOS ANGELES, CALIFORNIA.

AMALGAMATOR.

1,342,567.

Specification of Letters Patent. Patented June 8, 1920.

Application filed July 19, 1917, Serial No. 181,475. Renewed October 1, 1919. Serial No. 327,834.

To all whom it may concern:

Be it known that I, SAMUEL G. MUSSER, a citizen of the United States, residing at Los Angeles, in the county of Los Angeles and State of California, have invented a new and useful Amalgamator, of which the following is a specification.

This invention relates to amalgamators of the centrifugal type for separating and amalgamating gold or other metals from ores and consists in the provision of a simply constructed, inexpensive amalgamator which will provide for a maximum and complete amalgamation.

Other objects and advantages will appear during the course of the following description.

In the drawings:

Figure 1 is a view in elevation of the amalgamator showing one-half of the construction thereof in vertical section.

Fig. 2 is a cross sectional view taken on line x^2-x^2 of Fig. 1.

Fig. 3 is a cross sectional view taken on line x^3-x^3 , Fig. 1.

Fig. 4 is a fragmentary sectional view taken on line x^4-x^4 , Fig. 1.

Referring to the drawings, 1 designates a base member supporting an upright, preferably circular, housing 2 secured to the base 1 by bolts 3. A vertical shaft 4 is mounted centrally within the housing 2 and is journaled at its lower end within a bearing 5 carried upon the base 1. A pulley 6 is fixed to the shaft 4 and provides for the rotation thereof from a suitable source of power not shown.

Carried centrally of the housing is a tubular member 7 through which the shaft 4 extends. This member 7 is flared outwardly as at 8, at its lower end, the outwardly flared portion being formed integral as at 9 with the inner face of the housing 2 at a point below the upper end of the housing. There is provided a bearing 10 for the shaft at the upper end of the tubular member 7.

Amalgamating means in the form of an annular chamber or shell generally designated 11 is supported upon the upper end of and rotated by the shaft 4.

An annular pan 12 is secured by fastening means 13 to an annular flange 14 formed on the upper end of the housing 2. This pan surrounds the amalgamating means or chamber 11. Secured by bolts 14' to the upper edge of the pan is a ring 15 supporting an

arch 16 which carries a boss 17 in which is mounted an intake pipe 18. This pipe 18 is preferably threaded exteriorly, as at 19, upon its upper end to provide for its connection with an ore-feeding pipe or source not shown, and extends downwardly through the boss, terminating in an enlarged lower end portion 20, which is connected and communicated with the chamber or amalgamating means 11. It will be seen that the base 1, housing 2, pan 12 and arch 16, together with their coöperative elements, may be removed relative to one another and that the assembling or disassembling of this structure may be easily facilitated.

The amalgamating chamber 11 is formed in two parts, generally designated 21 and 22, the part 22 being in the form of an annular upwardly opening cup provided at its upper end and centrally with an enlarged portion or boss 23 which is keyed or otherwise fixed to the upper end of the shaft 4. This annular cup 22 extends downwardly between the inner wall 24 of the pan 12 and the tubular member 7 into the housing 2 and is adapted to rotate within said space, free from contact with the member 7 and wall 24. The part or section 21 of the amalgamating means or chamber 11 consists principally in an annular partition member 25 which extends into but is equidistantly spaced from the lower and opposed side walls of the annular cup 22 and provides inner and outer annular passages 26 and 27 communicated at their lower ends by an annular passage 28 formed between the bottom of the member 25 and bottom wall of the cup 22.

Discharge nipples 29 are formed at opposite points on the lower side of the cup 22 of the chamber and communicate with the passage 28. These nipples are preferably externally screw threaded, as at 30, and are provided with reduced screw threaded outer ends 31 upon which are mounted internally screw threaded caps 32 which are provided with plug members 32' extending into the nipples.

As shown by dotted lines in Fig. 1 of the drawings, there are provided discharge tubes 33 which, when it is desired to drain the amalgam from the chamber 11, are turned upon the screw threaded portions 30 of the nipples 29. These tubes 33 are extended through openings 34 and 35 respectively formed in the housing 2 and flared portion 8 of the tubular member 7.

By inserting a suitable tool when these tubes are positioned as shown in the drawings, the caps 32, which are of less diameter than the inside diameter of the tubes, may be unscrewed or removed and the nipples and the amalgam will readily drain from the chamber.

The partition member 25 is enlarged upon its upper edge providing an outwardly laterally extending annular portion 36 and a similar annular laterally extending portion 37 extending in the opposite direction. The portion 37 surrounds an eye-bolt 38 turned in the upper end of the shaft 4 and is formed in its upper face with an annular downwardly and outwardly inclined intake chamber 39 which communicates the lower enlarged end 20 of the intake pipe 18 with the outer annular passage 27. This chamber 39 is divided at equidistant points by a number of annular web portions 40, the latter acting to divide the chamber into passages 41 between the members 40. It will thus be seen that the ore fed to the chamber 39 will pass around the web portions 40 through the passages 41 into the passage 27. The enlargement 37 upon its underside in expanding laterally inwardly from the partition member 25 defines an annular shoulder 42. Extending upwardly and outwardly from the shoulder to a point on the outer annular face of the portion 36 are a series of passageways 43 which communicate the pan 12 with the inner annular passage 26. These passageways 43 extend through the annular web portions 40, as shown in Fig. 4 of the drawings, and at their discharge ends may be communicated with nozzles 44 which are secured by fastening elements 45 to the outer annular face of the portion 36 and which extend nearly tangentially from said outer annular face so as to discharge into the pan 12. These nozzles 44 may be omitted if desired, the passageways serving as nozzles. The engaging faces of the parts 21 and 22, more specifically the engaging faces of the enlarged portion 37 and boss or hub portion 23, are stepped or provided with a series of offsets defining shoulders 46. Screws or other fastening elements 47 are turned through the bottom wall of the chamber 39 and into the boss 23 so as to rigidly secure the two parts 21 and 22 of the amalgamating chamber 11. Screws 47 are turned through the portion 36 and into the outer wall of the cup 22 to secure the section of the chamber together.

The upper annular face 48 of the enlarged portion 37 surrounds the lower end of the enlarged portion 20 of the pipe 18 and secured upon said face 48 by a fastening element 49 is an annular flange 50 carried on the lower end of a sleeve 51. A packing gland 52 is mounted between the sleeve 51 and pipe 18 to provide a suitable stuffing box

that will prevent leakage. The enlarged portion 20 of the pipe 18 bears against the sleeve 51.

It will be seen that the amalgamator 11 consisting of the parts 21 and 22 may be readily assembled or disassembled without requiring the disassembling of the entire device and that it comprises a unit of simple and practical construction involving the use of comparatively little material. 75

Normally the mercury lies in the annular passage 28 at the bottom of the cup 22, but when the device is in operation and the shaft 4 rotates the chamber 11 the mercury is thrown outwardly by centrifugal force 80 and spreads in an annular film over the outer wall of the passage 27. In this connection it is noted that the outer wall of the passage 27, said outer wall being virtually the inner face of the outer wall of the cup 22, is inclined downwardly and inwardly. This inclination is provided in order that the film of mercury will be more evenly distributed. The upper edge of the outer wall of the cup 22 is enlarged, providing an annular shoulder 53 which extends over and is spaced from the upper edge of the inner wall 24 of the pan 12, and this enlargement also provides an inwardly extending annular shoulder 54 which acts as an abutment to prevent 95 the mercury from being thrown further upwardly by centrifugal force.

It is to be noted that the lower portion of the passage 27 extends inwardly and downwardly at an angle of 45° more or less from 100 the main portion of the passage to the point of its communication with the passage 28. This provides for the retention of the mercury during operation of the amalgamator. It will thus be seen that when the machine is 105 operated at sufficient rate of rotation the mercury forms the outer wall of the passage 27.

When the machine is in operation, as above described, and the ore is fed through 110 the pipe 18 into the chamber 39 it will pass around the webs 40 into the passages 41 and from thence downwardly into the passage 27. Since the chamber 11 is rapidly rotating the ore is forcibly thrown by centrifugal action against the thin mercury film or wall and intimately mixes with it. As the amalgamator may be rotated at high speed there is little likelihood of the ore becoming clogged and stopping up the passage 120 27 and the ore in being forcibly thrown into intimate contact with the mercury causes an effective and complete amalgamation of the metals.

The ore is preferably fed under pressure 125 to the passage 27 and will pass from said passage 27 through the passage 28 up the passage 26 and out through the passageways 43, discharging through the nozzles 44 into the pan. In this connection it will 130

be noted that the rapid rotation of the nozzles 44 causes centrifugal action upon the tailings issuing therefrom and in the passageways 43, thus providing for an effective discharge of the ore from the amalgamating chamber. The amalgam may be drained from the chamber by screwing the tubes 33 into the position shown in dotted lines in Fig. 1 of the drawings and then 10 moving the plugs 32. Upon the removal of the plugs 32 the amalgam will readily flow through the discharge nipples 29 and discharge from the tubes 35 where it may be suitably collected.

15 The pan 12 for receiving the tailings is provided with an outlet opening 55 and its bottom wall is inclined downwardly toward said opening so that ore thrown in the pan will readily pass out through opening 55.

20 From the foregoing it is clear that the centrifugal action of the tailings in the discharge end of the shell passage is sufficient to prevent clogging of the passage even though the force of the ore feed at the feed 25 end of the passage be insufficient of itself to cause the ore to flow through the machine at a desirable rate of speed. The advantage of this is that pressures inside of the shell may be minimized so as to minimize leakage past the packing 52 and through the 30 joints of the various sections of the shell, thus the centrifugal action of the hollow rotating column of ore is utilized to aid in moving the column of ore through and in 35 contact with a hollow body of mercury.

I claim:

1. A centrifugal amalgamator comprising a sectional shell, one section being in the shape of an annular cup and the other 40 section forming an annular partition spaced from the sides and bottom of the cup shaped section to form a restricted annular passage, the second named section having spaced webs and there being nozzle openings in the 45 webs communicating at their inner ends with the annular passage and extending to the periphery of the second named section.

2. In a centrifugal amalgamator, the combination of a shell having an annular passage, means to rotate the shell, an inlet for 50 the passage at the upper end of the shell, and nozzles at the periphery of the shell for the upper end of the passage, said nozzles being arranged to discharge in a direction opposite to the direction of rotation and the 55 passage from the inlet to the nozzle outlets being restricted and normally closed excepting as to the inlet and outlets and adapted to be normally filled with mercury and pulp while operating.

3. A centrifugal amalgamator comprising an upright revolving shaft, an annular cup open upon its upper side, a central web portion formed on the upper end of the cup and secured to the shaft, a feed pipe located 65 above the shaft, a support for the feed pipe, an annular pan surrounding the cup, a partition member mounted within the cup and spaced from the bottom and sides thereof providing upright annular passages communicating with one another at their lower 70 ends, an enlargement formed on the upper end of the partition member and extending over the web portion, said enlargement having an ore intake chamber in its upper side 75 and being provided with passages extending from the ore intake chamber to a point communicating with the upper side of the outer annular passage, said enlargement being formed with passages extending upwardly from points in communication with the upper side of the inner annular passage 80 to the outer peripheral face of said enlargement and adapted to discharge into the pan, and a charge of mercury which is distributed 85 over the outer wall of the outer annular passage by centrifugal action, said feed pipe extending into the chamber.

Signed at Los Angeles, California, this 11th day of July, 1917.
